REFRIGERATING APPARATUS

Charles F. Henney, Dayton, Ohio, assignor to
Frigidaire Corporation, Dayton, Ohio, a cor-
poration of Delaware

Application August 30, 1930, Serial No. 478,913
Renewed March 17, 1934

4 Claims. (Cl. 62—115)

This invention relates to refrigerating apparatus and more particularly to that type of apparatus in which at least two evaporators are maintained at different temperatures, or are so operated as to produce different temperatures in refrigerated spaces.

An object of this invention is to provide a refrigerating apparatus of the character above described in which operating efficiency is increased.

10 Further objects and advantages of the present invention will be apparent from the following description, reference being had to the accompanying drawings, wherein a preferred form of the present invention is clearly shown.

15 In the drawings:

Fig. 1 is a vertical cross-sectional view, somewhat diagrammatic of an apparatus embodying features of this invention;

20 Fig. 2 is a vertical cross-sectional view, somewhat diagrammatic of a modified form of the invention;

Fig. 3 is a horizontal cross-sectional view of the apparatus shown in Fig. 2; and

25 Fig. 4 is a diagrammatic illustration of a modified form of the invention.

In an apparatus wherein two evaporators have been connected to a single refrigerant liquefying unit it has been customary to provide means whereby different temperatures may be obtained 30 from the different evaporators. However, it has been generally necessary to operate the refrigerant liquefying unit in such a manner that substantially all of the liquefying operations have been carried on with a very low back pressure, 35 such back pressure usually corresponding to the pressure prevailing in the lowest temperature evaporator. According to this invention, however, it is possible to operate the high temperature evaporator or evaporators at back pressures 40 corresponding to their temperatures and to operate at low back pressure only when refrigeration is required in the low pressure evaporator or evaporators.

In the apparatus shown in Fig. 1, as a specific 45 embodiment, a soda fountain is provided with refrigerating means. The soda fountain, as here shown, includes a cabinet having insulated outer side, bottom and top walls and containing a compartment 10 for cooling drinking water, carbonated water and the like; a compartment 11 for cooling bottled drinks and the like and a compartment 12 for cooling ice cream and other foods requiring relatively low temperatures. Also an insulated syrup rail or compartment, 50 diagrammatically indicated at 13, is generally pro-

vided above the main part of the cabinet in which is kept the various syrups and flavors. Under ordinary circumstances, it is generally desired to maintain the compartment 10 at approximately 34° F., the compartment 11 at approximately 40° F., the compartment 12 at temperatures ranging from approximately 0° F. to 10° F., while the compartment 13 is generally maintained at approximately 50° F.

Sometimes the compartment 12 is within itself 10 provided with different temperatures, and, in this instance, it may be accomplished by providing a partition 14 so that the brine on the left side may be maintained at 0° F. while the brine on the right hand side may be maintained at approximately 15 7° F.

In order to refrigerate the soda fountain, a refrigerant liquefying unit 20 is provided which is connected by means of a liquid refrigerant line 21 with the evaporators hereinafter to be described and by the evaporated refrigerant line 22 which receives the refrigerant evaporated in the evaporators and returns the same to the unit 20. The unit 20 may be of the compressor-condenser type, if desired, and thus includes a compressor 23, a condenser 24, receiver 25, the latter being connected to the liquid refrigerant line 21. The compressor is operated by a motor 26 which is started and stopped by means of a snap switch 27 operated by the bellows 28 in a manner hereinafter to be more fully described.

The soda fountain is provided with a plurality of evaporators, and thus includes a high pressure evaporator 30, partly in the compartment 10 and partly in the compartment 13, and a low pressure evaporator 31 partly in the compartment 13 and partly in the compartment 12. An expansion valve 32 connects the line 21 with the evaporator 30 and an expansion valve 33 connects the evaporator 31 with the line 21. These valves are automatically controlled and are so arranged as to prevent flow of refrigerant into the evaporators at predetermined high pressure limits respectively and automatically open when the pressures in the evaporators drop below said predetermined limits. Thus the valve 32 automatically opens when the pressure within the evaporator 30 falls to a pressure corresponding to 34° F. which with SO₂ is approximately 9 pounds. The valve 33 automatically opens at a pressure corresponding with 0° F. which with SO₂ is 14 inches vacuum.

The expansion valve 32 is provided with a thermostatic control 34 for closing said valve when a predetermined low temperature has been 55

reached at a certain point in the high pressure evaporator. In this particular instance, the thermostatic control includes a bulb 35 connected to the valve 32 and is adapted to close the said valve when that portion of the evaporator 30 adjacent the bulb 35 reaches a predetermined low temperature, for instance 34° F. The bulb 35 may thus be soldered to the pipe forming part of the evaporator 30 at the point shown immediately above the level 36 of the liquid in the compartment, so that the bulb is not cooled to the predetermined temperature until the liquid in compartment 10 reaches that temperature.

The compartment 10 is filled with water or some liquid of similar freezing temperature and one or more coils 37 are placed in the compartment 10 through which drinking water, carbonated water and the like flows and is cooled by the liquid in the compartment 10 which liquid in turn is cooled by the submerged coils 30a of the evaporator 30.

The evaporator 30 continues in the form of a pipe 30b through the syrup rail 13 to a second valve 39. This valve preferably is of the snap acting type and is adapted to snap shut when the pressure in the evaporator 30 falls below a predetermined pressure, said pressure being below the pressure at which the valve 32 opens when not closed by the thermostatic control 34. The snap acting mechanism of the valve 39 is made responsive to the pressure within the evaporator 30, for instance for diagrammatic showing, through the tube 40. A type of valve suitable for valve 39 is disclosed in the application of Gilbert H. Williams, Serial No. 351,363, filed March 30, 1929. The valve 39 is set to open and close at pressures which SSO₂ would be 12 pounds and 0 pounds respectively. The evaporator 31 has a valve 33 similar to the valve 32, also provided with a thermostatic device 41, although this thermostatic device may, if desired, be omitted with the type of motor control shown in Figs. 1 to 3 inclusive. The thermostatic device 41 includes a bulb 42 connected to the outlet end of the pipe which terminates the evaporator 31 and is connected to the valve 33 to close the same when the bulb 42 reaches a predetermined low temperature. The evaporator 31 is also provided with a check valve 43 connecting the low pressure evaporator 31 with the evaporated refrigerant line 22. The check valve 43 is so arranged that it permits flow of the refrigerant from the evaporator 31 to the line 22 but prevents the flow from the line 22 to the evaporator 31.

Provisions for causing the refrigerant liquefying unit to operate in accordance with certain conditions in the evaporators is provided. Preferably the unit 20 is controlled by condensation, before return to the unit, of refrigerant evaporated in the high pressure evaporator 30. Thus a heat exchanging device 44 is constructed in the form of a downwardly directed loop in a pipe from the valve 39. This loop is in heat exchange relation to the evaporator 31. Control means responsive to the device 44 is provided for controlling the operation of the refrigerant liquefying unit 20 and this includes a thermostatic bulb 45 adjacent the loop 44, the bulb 45 being connected by means of the pipe 46 with the bellows which operates the snap switch 27 which controls the motor 26. When the valve 39 opens, evaporated refrigerant passes through the exchange device 44 and is there condensed by reason of the cold temperature of evaporator 31. The heat of condensation of the refrigerant in loop 44 warms

the bulb 45 and causes it to close the switch 27 and start the motor 26.

If the liquid in the compartment 10 requires refrigeration, the compressor begins evaporating refrigerant in the evaporator 30 and operates at a back pressure equal to the pressure at which the valve 32 is set to open. Refrigeration continues at this back pressure until such a time as the coil 30a adjacent the bulb 35 is cooled sufficiently to close the valve 32 by the action of the bulb 35. When the valve 32 is closed the compressor quickly pulls the pressure of the evaporator 30 down to such a pressure that it will cause the valve 39 to snap shut. When this happens the compressor 23 quickly pulls down the pressure in the line 22 to the point where valve 33 is opened permitting refrigerant to flow through the evaporator 31. The compressor then continues to run until such a time as the brine in the compartment 12 is cooled sufficiently to cause the bulb 45 to open the switch 27 and stop the compressor 23. In this system the compressor performs two-thirds of the work at the higher back pressure required in the evaporator 30. Since the difference in back pressure between the evaporators 30 and 31 is quite large, a substantial saving in operating cost is possible.

The evaporator 31 may also be used to aid in the cooling of the syrup rail 13. This is accomplished by providing a few bends of coil 31a in the syrup rail before passing the pipe comprising the evaporator 31 in the form of coils 31b and 31c around the sleeves in the compartment 12.

The compartment 12 in this particular embodiment includes a brine tank and a plurality of sleeves 51, 52 and 53. The refrigerant after passing through the coils 31a passes through the coil 31b surrounding the sleeve 51 and from thence as indicated through the coil 31c surrounding the sleeves 52 and 53 past the check valve 43 into the evaporated refrigerant line 22.

Figs. 2 and 3 show substantially the same system shown in Fig. 1 applied to a cabinet in which the ice cream sleeves are embedded in concrete. The corresponding parts of the refrigerating system are similarly numbered in these figures, with the exception that 100 has been added to the numbers. Thus the liquid refrigerant line 121 in Fig. 2 corresponds to the liquid refrigerant line 21 in Fig. 1, the same being true with respect to all other corresponding numbers.

In the modification shown in Figs. 2 and 3 the sleeve 151, instead of being submerged in a brine tank, is encased in a concrete casing 160. A large substantially square sleeve 152, 153 is encased in 55 a concrete casing 161 and is provided with a control metal plate to divide it into sub-compartments and to provide for conduction of heat. The casings 160 and 161 are placed around the sleeves after the coils 131b and 131c have been 60 placed around the sleeves 151, 152—153 respectively. The concrete is preferably quick drying Portland cement used without any sand or other ingredients except water. If desired, the coils 131b and 131c may be made of copper tubing with 65 fins attached thereto. The fins if desired may be a continuous spiral strip wound around the pipe. The cement is dried after it has set.

The loop 144 together with the bulb 145 is placed immediately outside the sleeve 151 and is also 70 embedded in the concrete sleeve 160.

The casings 160 and 161 rest on the cork board bottom 163 and are spaced from each other by a slab or cork 164. A second slab of cork 165 is placed on the other side of the casing 160 after 75

which loose ground cork 166 is poured between the slabs of cork and the casings 160 and 161. In these modifications the compressing unit preferably is identical with that shown in Fig. 1.

5 Fig. 4 shows how either of the modifications shown in Fig. 1 or in Figs. 2 and 3 may be provided with a slightly different motor control. Thus the refrigerant liquefying unit 220 may correspond to the motor 26, compressor 23, condenser 24 and 10 liquid refrigerant receiver 25 shown in Fig. 1. The refrigerant circuit shown diagrammatically in Fig. 4 corresponds in numbers with those shown in Fig. 1 with the exception that 200 has been added to the numbers. In addition, an 15 extra loop 270 is added after the bulb 42 of Fig. 1, the loop 270 being carried in the syrup rail 213 to act as a "drier" for the evaporated refrigerant after passing the bulb 242. The coils are placed in positions corresponding to those shown 20 in Fig. 1, it being understood that sleeves are placed within some of the coils and that another coil is submerged in liquid corresponding to compartment 10. The details of the cabinet have been omitted in Fig. 4 in order to show more clearly the refrigerating system.

25 The system shown in Fig. 4, is further modified with respect to the system shown in Fig. 1 by providing a "low pressure" control for the refrigerant liquefying unit 220. Thus the loop 44 and bulb 45 have been omitted in Fig. 4 and in lieu thereof the bulb 228 is actuated by the pressure in the evaporated refrigerant line 222, the bulb 228 merely being connected by a pipe 271 with the line 222, to be responsive to the pressure in 30 the low side of the system.

35 While the form of embodiment of the invention as herein disclosed, constitutes a preferred form, it is to be understood that other forms might be adopted, all coming within the scope of 40 the claims which follow.

45 1. Refrigerating apparatus comprising, in combination, a plurality of evaporators connected in parallel circuit relation; a common exhaust conduit for said evaporators; means for withdrawing gaseous refrigerant from the exhaust conduit, liquefying the refrigerant and returning the liquid to the evaporators; means for permitting and preventing the flow of refrigerant from one of the evaporators to the exhaust conduit;

and means for preventing the flow of gaseous refrigerant from said evaporator to the other evaporators when said last named means permits the flow of refrigerant from said evaporator to the exhaust conduit.

5 2. Refrigerating apparatus comprising, in combination, a pair of evaporators connected in parallel circuit relation; a common exhaust conduit connected to outlets of said evaporators; means for withdrawing gaseous refrigerant from the 10 exhaust conduit, liquefying the refrigerant and returning the liquid to the evaporators; means for permitting and preventing the flow of refrigerant from the outlet of one of said evaporators to the common exhaust conduit; and a check 15 valve connected between the outlet of the other evaporator and the exhaust conduit to prevent flow from the exhaust conduit to said other evaporator.

20 3. Refrigerating apparatus comprising, in combination a pair of evaporators connected in parallel circuit relation; a common exhaust conduit connected to outlets of said evaporators; means for withdrawing gaseous refrigerant from the exhaust conduit, liquefying the refrigerant and 25 returning the liquid to the evaporators; means responsive to the pressure of one of the evaporators for fully opening and positively closing its outlet to the exhaust conduit; and a check valve disposed between the outlet of the other evaporator and the exhaust conduit to prevent flow from 30 the exhaust conduit to said other evaporator.

4. Refrigerating apparatus comprising, in combination, a pair of evaporators connected in parallel circuit relation; a common exhaust conduit 35 connected to outlets of said evaporators; means for withdrawing gaseous refrigerant from the exhaust conduit, liquefying the refrigerant and returning the liquid to the evaporators; means responsive to the pressure of one of the evaporators for fully opening and positively closing its outlet to the exhaust conduit; and a check valve disposed between the outlet of the other evaporator and the exhaust conduit to prevent flow from the exhaust conduit to said other evaporator; and 45 means responsive to pressure of the exhaust conduit for starting and stopping the liquefying means.
